Application filed September 11, 1894. Serial No. 522,758. Term of patent 3½ years.

To all whom it may concern:

Be it known that I, GUSTAV KETTERER, a subject of the German Emperor, residing at Philadelphia, in the State of Pennsylvania, 5 have invented and produced a new and original Design for Wall-Paper, of which the following is a specification.

The design consists of an arrangement of groups of flowers and leaves of violets tied 10 with ribbons connected by festoons of the maiden-hair fern and loose violets placed irregularly over the surface of the paper as represented in the accompanying drawing. The border or upper portion of the design is 15 also formed of groups of flowers and leaves of violets tied with ribbons and connected by festoons of ribbons and festoons of maiden hair fern intertwined with the ribbon festoons

as shown in the drawing. Small groups of violets are also placed in the center of said 20 festoons. An ornamental band containing ribbon bows forms the top of the border and an ornamental band filled with violets forms the bottom of the border.

What I claim is—

1. The design for wall paper herein shown and described.
2. In the design for wall paper the border herein shown and described.
